[57] CLAIM

The ornamental design for a combined alpha-numeric keyboard and display module for a communication system or similar article, as shown and described.

DESCRIPTION

FIG. 1 is a reduced top end and side perspective view of a combined alpha-numeric keyboard and display module for a communication system or similar article showing my new design, the broken lines being shown for illustrative purposes only and form no part of the claimed design;

FIG. 2 is a top plan view thereof;

FIG. 3 is a side elevational view thereof opposite that shown in FIG. 1; and,

FIG. 4 is an end elevational view thereof opposite that shown in FIG. 1.

The bottom plan view is flat and unornamented.

FIG. 1

FIG. 2

FIG. 3

FIG. 4
